No. 846,141.

PATENTED MAR. 5, 1907.

J. RAPP,
COAL WASHER.
APPLICATION FILED OCT. 22, 1906.

UNITED STATES PATENT OFFICE.

JOSEPH RAPP, OF COLLINSVILLE, ILLINOIS, ASSIGNOR OF ONE-FOURTH TO
LOUIS F. LUMAGHI, OF COLLINSVILLE, ILLINOIS, AND ONE-FOURTH TO
JOSEPH D. LUMAGHI, OF ST. LOUIS, MISSOURI.

COAL-WASHER.

No. 846,141.

Specification of Letters Patent.

Patented March 5, 1907.

Application filed October 22, 1906. Serial No. 339,933.

To all whom it may concern:

Be it known that I, JOSEPH RAPP, a citizen of the United States of America, residing in Collinsville, in the county of Madison and 5 State of Illinois, have invented certain new and useful Improvements in Coal-Washers, of which the following is a full, clear, and exact description, reference being had to the accompanying drawings, forming part of this 10 specification.

My invention relates to improved means for operating the conveyers through the medium of which the refuse or foreign matter present with coal is delivered from coal-washers as it is discharged from the jig in which the coal is washed, a prime object of 15 the invention being to provide for the operation of the refuse-conveyer only during the periods of delivery of coal into the jig, thereby 20 avoiding unnecessary wear and tear on the machinery of the washer.

Figure I is a top or plan view of a coal-washer having my improvement embodied therein. Fig. II is a vertical longitudinal 25 section taken on line II II, Fig. I. Fig. III is an enlarged vertical cross-section taken on line III III, Fig. I, through the eccentric members associated with the driving-wheel of the conveyer-operating mechanism. Fig. 30 IV is a vertical section taken on line IV IV, Fig. I, through the driving-wheel of the conveyer-operating mechanism and the eccentric members associated with said wheel.

1 designates the washing-tank of a coal-washer, at the discharge end of which is a discharge-runway 2, onto which the coal is discharged as it is washed. 3 is a coal-delivery chute leading to the receiving end of the washer.

4 designates a jig having the usual inclined perforated bottom 5 and containing the outlet 6 for the discharge of refuse, such as slate. The jig is supported for rise-and-fall motion within the washing-tank by hangers 7, loosely 45 connected to shafts 8, applied to the jig, the hangers being provided at their upper ends with eccentric-boxes 9 in which the eccentrics 10, carried by rotatable shafts 11, operate. The shafts 11 have gear-wheels 12 50 fixed to them and intermeshing with each other, these wheels being driven by any suitable form of power connection.

13 is a refuse-receiving well located at the discharge end of the coal-washer and into which communication from the washing-tank is provided through the medium of an opening 1', located in a wall of the washing-tank, and with which the outlet 6 of the jig 4 is adapted to register in order that the slate or other refuse matter from the coal may be 55 delivered into said refuse-receiving well.

13' is a compartment located alongside of the refuse-well and having communication therewith.

14 is a conveyer, preferably of screw type, 60 which is located at the bottom of the refuse-receiving well and by which the refuse is conveyed from said well into the compartment 13'. The refuse is removed from the compartment 13' by a conveyer (not shown) 65 of any suitable form. The conveyer 14 is operated through means that will now be described.

15 designates a driving-wheel fixed to one of the rotatable jig-operating shafts 11, the 70 wheel being preferably of friction type.

16 is a shaft which is mounted in suitable journal-boxes supported by the frame of the coal-washer. This shaft 16 is provided with an eccentric 17. (See Figs. II, III, and IV.) 75

18 is a driving-wheel, preferably of friction type, which opposes the driving-wheel 15 and which is mounted on the shaft 16 at the location of the eccentric 17 to provide for said eccentric operating within said wheel. The 80 wheel 18 has an extended belt-receiving hub 19, which is preferably provided with teeth to form a sprocket-wheel that receives an endless chain belt 20.

21 is a shaft journaled in suitable boxes on 85 the frame of the washer and to which is fixed a belt-receiving wheel 22, on which the belt 20 operates. The shaft 21 also has fixed to it a driving-wheel 23, that receives a belt 24, which leads to a wheel fixed to the shaft of 90 the conveyer 14 and serves to drive said conveyer for refuse-discharging action.

27 designates a lever rockingly supported by a rod 28, suitably attached to the frame of the washer. This lever has fixed to its 100 lower end a plate or pan 29, that is located at the lower end of the coal-delivery chute 3 in order that the coal delivered from said chute into the jig 4 will constantly strike

against said plate or pan before descending into the jig and cause the upper end of the lever to be thrown in a direction toward the delivery-chute.

5 30 is a pull-rod having its forward end connected at 31 to the upper end of the lever 27.

32 is a crank-arm fixed to the shaft 16, which is provided with an eccentric 17 and on which the driving-wheel 18 is mounted. This 10 crank-arm has the pull-rod 30 pivotally connected thereto at 33.

34 is a counterbalance or retracting weight mounted upon the rear end of the pull-rod 30.

In the operation of a coal-washer having 15 my improvement embodied therein when the coal is delivered from the delivery-chute 3 it acts, by striking against the pan or plate 29, to hold the upper end of the lever 27 in a forward position, and this lever constantly exerts a pull upon the pull-rod 30, as a result of which the crank-arm 32 is held in a forward position. When said crank-arm is moved forwardly, due to the forward movement of the pull-rod, the shaft 16 is rocked and the 20 eccentric 17 is moved sufficiently to cause it to act against the driving-wheel 18 surrounding it and shift said driving-wheel in a direction toward the opposing driving-wheel 15 on one of the jig-operating shafts, and motion is 25 therefore caused to be transmitted from the jig-operating shaft-driving wheel to the first-named wheel—viz., the wheel 18. The wheel 18 being put in motion serves to drive the belt 20. Said belt in turn serves to drive the shaft 21, and said shaft drives the conveyer 14 through the medium of the belt 26. Immediately upon the delivery of coal ceasing the pan or plate 29 returns to its normal 30 position, due to the impact of coal against the pan or plate being discontinued. The return of the pan or plate to its normal position is occasioned through the medium of a counterbalance-weight 34, which causes the 35 levers with which it is associated to be tilted and the eccentric 17 to be rotated sufficiently to remove the driving-wheel 18 from engagement with the driving-wheel 15 on the jig-operating shaft to which it is applied, with the result of discontinuing the operation of 40 the refuse-conveyer until delivery of coal is again resumed. Due to the provision of the well 13 of my coal-washer and the fact that said well has communication with the jig of the washer I am enabled to control the outlet 45 of refuse from said jig and also to prevent discharge or waste of coal through the refuse-outlet. This is due to the fact that the jig waste-outlet and the aperture opening into the refuse-well are constantly occupied by 50 refuse, and when the operation of the conveyer 14 ceases the refuse in the jig-outlet and aperture just referred to serves to prevent the exit of the coal into the refuse-well. It will therefore be seen that at no time is it

possible for coal to be discharged with the 65 refuse.

I claim—

1. In a coal-washer, the combination with a jig and a jig-operating member, of a refuse-receiving well, a conveyer operatable in said well, and conveyer-operating means driven by said jig-operating member adapted to be automatically thrown into and out of coöperation with said jig-operating member by variations in the feed of the washer, substantially as set forth. 75

2. In a coal-washer, the combination with a jig, and a jig-operating member, of a refuse-receiving well, a conveyer operatable in said well, conveyer-operating means adapted to be driven by said jig-operating member, and means acted upon by the coal entering said jig for moving said conveyer-operating means into coöperation with said jig-operating member, substantially as set forth. 80

3. In a coal-washer, the combination with a jig and a jig-operating member, of a refuse-receiving well, a conveyer operatable in said well, a driving member arranged for coöperation with said jig-operating member, means coöperating with said driving member for operating said conveyer, and means acted upon by the coal entering said jig for moving said driving member toward and away from said jig-operating member, substantially as set 95 forth. 90

4. In a coal-washer, the combination with a jig and a jig-operating member, of a refuse-receiving well, a conveyer operatable in said well, a driving member arranged for coöperation with said jig-operating member, means coöperating with said driving member for operating said conveyer, and lever mechanism 100 acted upon by the coal entering the jig for moving said driving member into and out of engagement with said jig-operating member, substantially as set forth. 105

5. In a coal-washer, the combination with a jig and a jig-operating member, of a refuse-receiving well, a conveyer operatable in said well, a shiftable driving member arranged for coöperation with said jig-operating member, means coöperating with said driving member for operating said conveyer, and a lever having connection with said driving member for shifting it to and from said jig-operating member and having a part adapted to be acted upon by the coal entering said jig, substantially as set forth. 110 115

6. In a coal-washer, the combination with a jig and a jig-operating shaft, of a driving-wheel mounted on said shaft, a refuse-receiving well, a conveyer operatable in said well, a driven shaft, a driving-wheel mounted on said driven shaft, driving means connecting said last-named driving-wheel to said conveyer, a shifting member associated with said last-named driving-wheel for moving it to and 120 125

from said first-named driving-wheel, and means acted upon by the coal entering said jig for moving said shifting member, substantially as set forth.

5 7. In a coal-washer, the combination with
a jig and a shaft for operating said jig, of a
driving-wheel on said shaft, a refuse-receiving
well, a conveyer operatable in said well,
a suitably-supported conveyer-operating

- 10 wheel arranged for engagement with said shaft-carried wheel, and means acted upon by the coal entering said jig for shifting said conveyer - driving wheel to and from said first-named wheel, substantially as set forth.

15 8. In a coal-washer, the combination with a jig and a shaft for operating said jig, of a driving-wheel on said shaft, a refuse-receiving well, a conveyer operatable in said well, a suitably-supported conveyer-operating wheel

20 arranged for engagement with said shaft-carried wheel, and lever mechanism acted upon by the coal entering said jig for automatically shifting said conveyer-driving wheel to and from said first-named wheel, substantially as
25 set forth.

9. In a coal-washer, the combination with

a jig and a shaft for operating said jig, of a driving-wheel on said shaft, a refuse-receiving well, a conveyer operatable in said well, 30 a suitably-supported conveyer-operating wheel arranged for engagement with said

wheel arranged for engagement with said shaft-carried wheel, and lever mechanism acted upon by the coal entering said jig for shifting said conveyer-driving wheel to and from said first-named wheel; said lever mechanism being provided with a counter-

mechanism being provided with a counter-balance-weight, substantially as set forth.

10. In a coal-washer, the combination with a jig and a shaft for operating said jig, 40 of a driving-wheel on said shaft, a refuse-receiving well, a conveyor operable in said

ing wheel arranged for engagement with said shaft-carried wheel, and means for shifting said conveyer-driving wheel to and from said first-named wheel and comprising an eccentric coöperating with said conveyer-driving wheel, and means adapted to be acted upon by coal entering said jig for moving said eccentric, substantially as set forth. 45

11. In a coal-washer, the combination with a jig and a shaft for operating said jig, of a driving-wheel on said shaft, a refuse-receiving well, a conveyer operatable in said well, a suitably-supported conveyer-operating wheel arranged for engagement with said shaft-carried wheel, and means for shifting said conveyer-driving wheel to and from said first-named wheel and comprising an eccentric coöperating with said conveyer-driving wheel, and lever mechanism having connection with said eccentric adapted to be acted upon by the coal entering said jig, substantially as set forth. 55 60

12. In a coal-washer, the combination 65
with a jig and a shaft for operating said jig,
of a driving-wheel on said shaft, a refuse-re-
ceiving well, a conveyer operatable in said
well, a suitably-supported conveyer-operat-
ing wheel arranged for engagement with said
shaft-carried wheel, and means for shifting
said conveyer-driving wheel to and from said
first-named wheel and comprising an eccen-
tric coöperating with said conveyer-driving
wheel, and lever mechanism having connec-
tion with said eccentric and adapted to be
acted upon by the coal entering said jig;
said lever mechanism being provided with
a counterbalance-weight, substantially as
set forth. 70 75

JOSEPH RAPP.
